COUCH

Elmer T. Wuest and Herbert A. Wuest, Cincinnati, Ohio, assignors to Adam Wuest, Inc., Cincinnati, Ohio, a corporation of Ohio

Application January 31, 1936, Serial No. 61,798

16 Claims. (Cl. 5—18)

This invention relates to a couch, and especially to means whereby the couch may be manipulated or extended to provide a bed.

An object of the invention is to provide an extensible couch or the like with novel actuating means whereby a tracial or movable section of the couch may be extended or retracted with the expenditure of a minimum of time and effort, and without requiring the operator to stoop or to lift any part of the couch.

Another object of the invention is to accomplish the foregoing object by the employment of means which are simple and inexpensive, durable, and of such character as to be either normally concealed, or exposed in such a manner as to enhance the appearance of the couch.

The foregoing and other objects are attained by the means described herein and disclosed in the accompanying drawings, in which:

20 Fig. 1 is a perspective view of a couch embodying the present invention.

Fig. 2 is a plan view of the Fig. 1 device, the covering material being broken away.

25 Fig. 3 is a perspective view of an actuating means of the invention.

Fig. 4 is a fragmental perspective view showing a second form of actuating means.

30 Fig. 5 is a fragmental elevational view showing a third form of actuating means.

Fig. 6 is a plan view of the couch, with the covering material removed, showing a construction adapted for use with either actuating means of Figs. 4 and 5.

35 Fig. 7 is a perspective view of a modification.

The couch, or so called studio couch, illustrated in the drawings, comprises a stationary frame 8 and a relatively movable frame 9 which, if desired, may be rendered tracial by the provision of suitable rollers 10. The movable or tracial frame 9 may comprise the various legs 12 which support a rectangular structure 13 having associated therewith any suitable type of mattress supporting means 14. The means 14 illustrated in the drawings, is a wire fabric attached to the rectangular frame elements by means of a multiplicity of springs 15. The movable frame may conveniently be built of angle iron sections.

50 The stationary frame may comprise a suitably upholstered seat portion 16 having front legs 17 and rear legs 20, or an equivalent structure for spacing the seat structure from the floor a distance sufficient to permit retraction of the movable frame to a position beneath the seat structure 16. The stationary frame 8 may in-

clude a back rest, if desired, which may be in the form of a panel or a rail such as 18 supported at its ends upon rear uprights 19. The uprights referred to may provide also the rear legs 20 of the stationary frame, (see Fig. 1). It will be noted that the rail 18, when the rail type of back rest is utilized, is spaced from the plane of the seat portion 16. The rail is adapted to provide a support for pillows which stand on edge upon the seat portion 16 near the rear thereof. 10

The stationary and movable frames are adapted to be connected together in any suitable manner, to limit the movement of the tracial frame outwardly, and to guide and stabilize said frame when moved relative to the stationary frame. To this end, there is provided the scissors arrangement of crossed bars 21 and 22. As is most clearly illustrated in Fig. 2, the bar 21 has its rear end pivoted at 23 upon or relative to the stationary frame 8, adjacent the rear portion thereof, and the bar 22 has its forward end pivoted at 24, upon or relative to the inner frame member 25, of the movable frame 9. The opposite ends of the crossed bars are received in the slots 26 and 27 of the stationary and movable frames, respectively. Such slots may be formed in the frames, if desired, or they may be formed in separate parts attached to the frames, in accordance with common practice. Each bar may carry a lug 28 to ride in its associated slot. From 30 the foregoing, it will be evident that retraction of the movable frame 9 to a position beneath the stationary frame 8, in Fig. 2, will cause the lugs 28 of the crossed bars to travel along the slots 26 and 27, to a position at the extreme left-hand end thereof (referring to Fig. 2). During the movement referred to, the frame 9 will be definitely stabilized and guided to its retracted position. The stabilizing and guiding function occurs also upon extending the movable frame. 40 It should be noted that the crossed bars 21 and 22 are pivoted together at a point 29 intermediate their ends.

In accordance with the invention, means are provided for mechanically extending and re- 45 retracting the movable frame 9. The said means may be referred to generally as an actuating means which, in Figs. 1, 2, and 3, comprises a horizontal handle or lever 30 to be swung through substantially a quarter-circle arc, and arranged 50 to project the movable frame when disposed in the full line position of Fig. 1, and to retract the frame when moved to the dotted line position indicated by the character 31. Particular attention is directed to the fact that in the in- 55

operative or dotted line position indicated, the handle or lever is disposed substantially within or parallel to the plane of the back rail 18, in such a manner that it will not interfere with the placing of cushions against the back rail. When the handle or lever 30 is moved to the forwardly extended position of Figs. 1 and 2, it is substantially parallel to the side of the couch, so as not to interfere with the use thereof as a bed.

10 The handle 30 is operatively connected to the movable frame 9 by means of a horizontal swing bar or the like 32. Both the swing bar and the handle are fixedly mounted upon a vertical pivot rod 33, the ends of which pivot rod are journaled in bearings 4 and 5 carried by the upright or standard 19. The bearings may be individual or separate, as shown in Fig. 7, or they may be in the form of perforated extensions 36 and 37 of a bracket 38. The members 30 and 32 may be 15 fixed to the pivot rod in substantially parallel and spaced relationship. The means providing the bearings may be screwed, bolted, or otherwise secured to one of the rear uprights, for example, upright 20. Thus, the pivot rod 33 is enabled to 20 rotate through an arc of approximately ninety 25 degrees (90°), while handle 30 and the rod 32 swing in substantially horizontal planes.

At the free end of the swing bar 32 there is 30 provided a follower 41, which may be in the form of an upwardly or downwardly turned section of the bar, the follower being adapted for movement within a guideway or track 42 associated with the movable frame 9. The guideway or track may be made in various forms, there being shown 35 a satisfactory construction comprising a member 43 spaced from the rail 25 but secured thereto by means of rivets or other fasteners 44. The spacing between member 43 and rail 25 is sufficient to receive the follower 41 of the swing bar, 40 and the guide bar may be of a length approximating the length of said swing bar 32. The construction just described provides for automatic retraction and extension of the movable frame 9, when the lever or handle 30 is moved 45 from the full line position of Fig. 1 to the dotted line position indicated at 31, and vice versa.

The horizontal swing bar 32 preferably, but not necessarily, moves in substantially the plane of the supporting surface 14 of the removable frame. 50 This results in extreme simplicity, elimination of parts, and compactness of the structure. It is to be understood that the guideway or track 42—43 may be dispensed with if desired, by connecting the free end of the swing bar to the movable frame otherwise than as illustrated in Fig. 55 1, for example, by means of a link 39 (Fig. 7) pivoted at its ends to the swing bar and to the frame or scissors structure. Also, the guideway or track may take other forms that will readily 60 suggest themselves after a study of the present disclosure. The exact shape or configuration of the handle 30 is immaterial to the invention.

In accordance with Fig. 4, which is a modification, the handle 130 extends forwardly of the couch while the swing bar 132 is in the inoperative or retracted position. In other words, the swing bar and the handle are fixed to the vertical pivot rod 133 at right angles to one another. It will be noted also that the actuating handle 130 is 65 turned upon itself as at 45, so as to extend about 70 the rear upright 19 and then project forwardly and downwardly, terminating in a forward end 46 which may abut the stationary frame 8. The reference character 47 indicates a latch of conventional design, for detachably fixing the for-

ward end of the arm to a part of the stationary frame. In this construction, the bracket 138 is the same as that of Fig. 3, but the arrangement of the actuating lever or handle 130 is such that the tractive frame (not shown on Fig. 4) will be extended upon swinging movement of the handle or lever 130 outwardly from the side of the couch. Thus, when the device is extended, the handle or lever 130 will assume a position outside the body line of the couch but substantially in 10 the plane of the back rest 18. It will be understood that the actuating mechanism of Fig. 4 is adapted to be associated with the movable and stationary frame parts in the manner disclosed in Figs. 1 and 2, or its association with the couch parts may be in accordance with the teaching of Fig. 7.

Attention is now directed to the modification illustrated by Fig. 6 wherein the swing bar 48 is arranged to apply force upon the scissors arrangement comprising the bars 49 and 50, at or near the pivotal connection 51 thereof, instead of applying such force directly upon the movable or tractive frame. The scissors arrangement of the Fig. 6 construction is identical with that of Fig. 1 and Fig. 2, wherefore the explanation thereof need not be repeated. It will be understood, however, that by connecting the swing bar 48 to the pivot 51 or to the scissors arrangement, the vertical pivot rod 52 (which corresponds with the rods 33 and 133 of Figs. 3 and 4) is greatly limited in its rotational movement. The approximate movement of the swing bar 48 is indicated by the angle between the full line position of Fig. 6 and the dotted line position thereof as indicated by the character 53. Because of the limited swinging movement of the swing bar, and of any handle that might be associated therewith, it will be seen that a handle such as that of Fig. 1 could not conveniently be employed, as it would 30 objectionably extend across the bed and within the body lines thereof. The invention contemplates the application of a handle means of the Fig. 4 character, however, to the Fig. 6 construction, for such a handle would swing outwardly 35 of the side of the couch upon extension of the movable frame. The manner of applying the handle 130 of Fig. 4 to the Fig. 6 construction is indicated generally by the broken lines 130. Should it be desirable, however, to apply the 40 principle of the Fig. 1 handle, to the Fig. 6 understructure, a means such as is disclosed in Fig. 5 is applicable. In accordance with Fig. 5, the 45 actuating handle or lever 54 is not fixedly secured to the vertical pivot rod 55, but has a sort of ratchet connection therewith. The connection 50 may be more properly referred to as a lost-motion joint, one form of which is illustrated. Said joint may comprise a bayonet slot 56 in a tube 57 which surrounds and is fixed to the pivot rod, 55 said bayonet slot being adapted to receive an extending lug or stud 58 carried by the handle or lever. By means of the lost-motion connection, the swing bar 59 may be moved through the limited arc as explained in connection with the Fig. 6 actuating means, by movement of the handle 54 through a similar arc. Upon completion of 60 said arcuate movement, however, the lug 58 would move through horizontal way 60 of the bayonet slot, for easily disposing the handle or lever 54 to the concealed position beneath the rail 18 of the back rest. It will be understood that the type 65 of handle or lever action disclosed in Fig. 5 is applicable to the particular construction shown in Fig. 6 but that it could be applied also to the 70 75

extending and retracting means of Fig. 2, if desired. It will be noted in connection with Fig. 6, that the free end of the swing bar 48 is provided with a slot 61 in which the pivot 51 may ride when the device is manipulated to extend or retract the movable frame. It may be stated also that the slot 61 may be obviated, if desired, by connecting the free end of the swing bar to the pivot 51, or to any other part of the scissors arrangement, by means of the pivoted connecting link arrangement illustrated in Fig. 7.

In conclusion, attention is directed to the fact that couches embodying the present invention need not be provided with a back rest, (see Fig. 7). The upright or post 19 may be short, or just long enough to provide a suitable support for bearing means such as 34—35. In fact, the upright or post may be the rear leg of the couch, and the handle or lever 30 may be at an elevation approximating the plane of the mattress with which the frame 3 is to be equipped, so that the handle or lever may be swung over the mattress in the manner previously explained in connection with Figs. 1 and 2. Fig. 7 suggests also the possibility of having the handle or lever 30 to furnish, of itself, a back rest or a portion of a back rest, while the couch is in the normally retracted condition.

It is to be understood that various other modifications and changes in the structural details of the device may be made, within the scope of the appended claims without departing from the spirit of the invention.

What is claimed is:

35 1. A convertible couch comprising in combination a stationary frame including a seat portion and a supporting standard in angular relationship to the plane of the seat portion, a shiftable frame arranged for movement to extended and retracted positions relative to the stationary frame, bearing means fixed relative to said supporting standard, an upright pivot rod rotatably supported by the bearing means, a hand lever and a swing bar supported by said upright pivot rod at different elevations upon the pivot rod, said hand lever being elongated so as to make a wide swing over and above the seat portion of the stationary frame, to a position such as an arm rest normally occupies, and means cooperating with the swing bar to effect an extension of said shiftable frame upon rotation of the upright pivot rod by the hand lever upon being swung to the position stated.

55 2. A convertible couch comprising in combination a stationary frame including a seat portion and a support, a shiftable frame arranged for movement to extended and retracted positions relative to the stationary frame, bearing means fixed relative to said support, an upright pivot rod rotatably supported by the bearing means, a hand lever and a swing bar supported by said upright pivot rod, means to effect an extension of said shiftable frame upon rotation of the upright pivot rod and its swing bar by the hand lever, and a lost-motion connection between the upright pivot rod and the hand lever, enabling dis- position of the hand lever to a position other than the position assumed thereby when moved to extend the shiftable frame.

70 3. A convertible couch comprising in combination a stationary frame including a seat portion, a back rest disposed along the rear edge of the seat portion, and means for supporting the back rest in spaced relationship to the plane of the seat portion, a shiftable frame arranged for movement to extended and retracted positions relative to the stationary frame, means carried by said shiftable frame providing an elongated guideway of a length approximately the width of the stationary frame, a manipulatable swing bar pivotally supported upon the stationary frame and reaching approximately across the width of said frame for movement through an arc, and a follower on one end of the swing bar, for engaging the elongated guideway of the shiftable frame during manipulation of the swing bar.

75 movement to extended and retracted positions relative to the stationary frame, bearing means fixed relative to said back rest supporting means, an upright pivot rod rotatably supported by the bearing means, a hand lever supported by said upright pivot rod substantially at right angles thereto, so as to be capable of a swinging movement horizontally across the seat portion of the couch, and to a position of substantial concealment beneath the spaced back rest, and means connected to the upright pivot rod for extending the shiftable frame as the hand lever is manipulated in the manner stated.

4. A convertible couch comprising in combination a stationary frame including a seat portion, a shiftable frame arranged for movement to extended and retracted positions relative to the stationary frame, and means for thus moving said frame, comprising a pair of scissors arms pivoted together intermediate their ends, corresponding ends being pivoted one to the stationary frame and one to the shiftable frame, and opposite corresponding ends being shiftably connected, each one to one of the frames, a movable hand lever mounted upon the couch, and means connecting the hand lever to one of the scissors arms for actuating said arms and extending the shiftable frame.

5. A convertible couch comprising in combination a stationary frame including a seat portion, a shiftable frame arranged for movement to extended and retracted positions relative to the stationary frame, and means for guiding said shiftable frame, a hand lever to be manipulated for extending the shiftable frame, means pivoting the hand lever upon one corner of the stationary frame for arcuate swinging movement in a plane substantially parallel to the seat portion of the stationary frame toward and from an arm-rest position, and means for transmitting said movement of the hand lever to the shiftable frame, for extending said frame.

6. A convertible couch comprising in combination a stationary frame including a seat portion, a shiftable frame arranged for movement to extended and retracted positions relative to the stationary frame, means for guiding said shiftable frame, means carried by said shiftable frame providing an elongated guideway of a length approximately the width of the stationary frame, a manipulatable swing bar pivotally supported upon the stationary frame and reaching approximately across the width of said frame for movement through an arc, and a follower on one end of the swing bar, for engaging the elongated guideway of the shiftable frame during manipulation of the swing bar.

7. A convertible couch comprising in combination a stationary frame including a seat portion, a back rest disposed along the rear edge of the seat portion, and means for supporting the back rest in spaced relationship to the plane of the seat portion, a shiftable frame arranged for movement to extended and retracted positions relative to the stationary frame, means carried by said shiftable frame providing an elongated guideway, a swing bar pivotally supported at one end upon the stationary frame for movement through an arc, a follower near the opposite end of the swing bar, for engaging the elongated guideway of the shiftable frame, and a manipulating lever associated with the swing bar, for swinging movement from a position beneath the back rest to a position overhanging the seat portion.

8. A convertible couch comprising in combination a stationary frame including a seat portion, a back rest disposed along the rear edge of the seat portion, and means for supporting the back rest in spaced relationship to the plane of the seat portion, a shiftable frame arranged for movement to extended and retracted positions relative to the stationary frame, means carried by said shiftable frame providing an elongated guideway, a swing bar pivotally supported at one end upon the stationary frame for movement through a circle arc, a follower near the opposite end of the swing bar, for engaging the elongated guideway of the shiftable frame, a manipulating lever associated with the swing bar, for swinging movement from a position beneath the back rest to a position overhanging the seat portion, and means whereby the manipulating lever is afforded limited swinging movement independently 20 of the swing bar.
9. A convertible couch comprising in combination a substantially horizontal stationary frame, a shiftable frame arranged for movement to extended and retracted positions relative to the stationary frame, and means for actuating said shiftable frame, comprising a swing bar and a link, said link pivotally connecting one end of the swing bar to a part of the shiftable frame, and means including an extensive lever mounted 30 for arcuate movement above and over a substantial area of the stationary frame, and in a plane substantially parallel to the plane of the stationary frame, for moving the swing bar.
10. A convertible couch comprising in combination a stationary frame including a seat portion, a shiftable frame arranged for movement to extended and retracted positions relative to the stationary frame, and means for guiding said frame, comprising a pair of scissors arms pivoted 40 together intermediate their ends, corresponding ends being pivoted one to the stationary frame and one to the shiftable frame, and opposite corresponding ends being shiftably connected, each one to one of the frames, a manipulating lever mounted upon the couch for movement 45 above and over the seat portion, and means including a swing bar, associated with the lever, and a link on the swing bar, for transmitting movement of the lever to the shiftable frame.
11. A convertible couch comprising in combination a stationary frame including a seat portion, a shiftable frame arranged for movement to extended and retracted positions relative to the stationary frame, and means for guiding said frame, comprising a pair of scissors arms pivoted 55 together intermediate their ends, corresponding ends being pivoted one to the stationary frame and one to the shiftable frame, and opposite corresponding ends being shiftably connected, each one to one of the frames, a substantially 60 vertical pivot rod journaled on the stationary frame, a manipulating lever fixed to the pivot rod for extension transversely therefrom and normally providing an arm rest for the couch, and means associated with the lever for transmitting 65 movement of the lever to the shiftable frame.
12. A convertible couch comprising in combination a stationary rectangular frame including a seat portion, a shiftable frame arranged 70 for movement to extended and retracted positions relative to the stationary frame, and means for actuating said shiftable frame, comprising an upright pivot rod rotatably supported at one corner of the stationary frame, an extensive lever 75 movable with the pivot rod and adapted to be arcuately swung in a plane substantially parallel to the plane of the seat portion of the stationary frame and over a substantial area of the seat portion adjacent to said one corner at which the pivot rod is supported, a swing bar movable with 5 the pivot rod to describe an arc beneath the seat portion, and a link having opposite ends pivoted relative to the shiftable frame and to the swing bar, for extension of said frame upon manipulation 10 of the lever arcuately as stated.
13. A convertible couch comprising in combination a stationary rectangular frame including a seat portion having ends, a forward edge, and a rear edge, a shiftable frame substantially parallel to the seat portion and arranged for movement to extended and retracted positions relative to the stationary frame, cooperative means on the frames for effecting said movements of the shiftable frame to the extended and retracted positions and including an upright 15 rotatable rod having an elongated manipulating lever supported thereon to overhang the seat portion at an elevation above and in substantial parallelism with the seat portion, and bearing means rotatably supporting said rod close to one 20 corner of the stationary frame, so that the lever, when swung to rotate the rod, will describe an arc of a circle whose center is located approximately at that corner of the frame at which the bearing means is located, the lever being thereby 25 movable over a substantial area of the seat portion from a position lengthwise of the rear edge of the seat portion to a second position lengthwise of an end of the seat portion.
14. A convertible couch comprising in combination a stationary rectangular frame including a seat portion having ends, a forward edge, and a rear edge, a shiftable frame substantially parallel to the seat portion and movable to extended and retracted positions relative to the 30 stationary frame, cooperative means on the frames for effecting said movements of the shiftable frame to the extended and retracted positions and including an upright rotatable rod having an elongated manipulating lever supported upon the rod at an elevation above the 35 seat portion, and bearing means rotatably supporting said upright rod close to a rear corner of the stationary frame, so that the lever, when swung to rotate the rod, will assume an arm-rest 40 position and describe an arc of a circle whose center is located approximately at one rear corner of the couch.
15. A convertible couch comprising in combination a stationary rectangular frame including a seat portion having ends, a forward edge, and a rear edge, a shiftable frame substantially parallel to the seat portion and movable to extended and retracted positions relative to the stationary frame, cooperative means on the 50 frames for effecting said movements of the shiftable frame to the extended and retracted positions and including an upright rotatable rod, an arm rest mounted upon and movable with the rod, at an elevation above the seat portion, and bearing means rotatably supporting said upright 55 rod close to a rear corner of the stationary frame, so that the arm rest may be swung from a normal arm-supporting position along the seat portion end, to rotate the rod and thereby shift the 60 movable frame, and latch means for precluding accidental swinging movement of the arm rest from the normal arm-supporting position.
16. A convertible couch comprising in combination a stationary frame including a seat por- 75

tion, a shiftable frame arranged for movement beneath the seat portion to extended and retracted positions relative to the stationary frame, means carried by said shiftable frame providing 5 an elongated guide-way of a length approximating half the length of the shiftable frame, a swing bar of a length approximating the width of the stationary frame and pivotally supported at one end upon the stationary frame for movement through an arc, a follower near the op-

posite end of the swing bar, for engaging the elongated guide-way of the shiftable frame, and a manipulating lever mounted for movement with the swing bar, for arcuately advancing the follower along the guide-way in opposite directions 5 to extend and retract the shiftable frame relative to the stationary frame.

ELMER T. WUEST.
HERBERT A. WUEST. 10
